UNITED STATES PATENT OFFICE

JOHN STRIDLUND, OF TOFTE, NORWAY

BARKING DRUM

Application filed July 16, 1928, Serial No. 293,114, and in Sweden February 5, 1927.

The present invention relates to an improvement in barking drums of the type which rotate partially submerged in water, and which are provided on their inner sides 5 with ribs or the like which during the rotation of the drum catch and lift the logs in the drum and then allow them to fall, each such drum being supported by two endless chains each of which runs around the drum 10 and also over a chain-wheel.

The invention resides principally in that each chain-wheel is adjustably mounted in the vertical direction for the purpose of rendering possible adjustment of the position 15 of the drum in the vertical direction according as the chains become worn. Preferably, one of said chain-wheels also serves as a driving wheel for the drum, being for this purpose connected to a suitable driving device. 20 This arrangement provides a very simple and reliably operating barking drum.

In the accompanying drawings a few embodiments of the invention is illustrated by way of example. Fig. 1 shows a side view 25 of a barking drum according to the invention, Fig. 2 shows a top plan view of the drum, and Fig. 3 shows an end view of the drum. In Figs. 1 and 2 the drum is shown with less than its proportional length, for want of space. 30 Fig. 4 shows to a larger scale a detail view of the ribs provided on the inside of the drum. Fig. 5 shows an end view of a slightly modified construction of a barking drum.

The barking drum illustrated consists of 35 two separate drums 1, which are placed in alignment and close to one another so that they operate as a single barking drum. The drums may be constructed, for instance, of bars or ribs 2 of heavy sheet iron which are 40 riveted to the inside of rings 3 of channel iron, and are spaced apart so as to form longitudinal slots 4 between said bars, through which slots the water may flow in and out when the drums are caused to rotate partially 45 submerged in a tank 5 containing water.

Each drum is supported by two endless chains 6, each of which runs around the drum between two guide rings 7 and over a single chain-wheel 8, which suitably should have a 50 less diameter than the drum. Each chain-

wheel 8 is rotatably journaled in a lever 9, which is pivoted at one end on a horizontal shaft 10 and is supported at the other end by a tackle block 11 by means of which the lever, and thus also the chain-wheel 8 journaled 55 therein, may be raised and lowered. In the construction illustrated in Figs. 1 to 3, one of the two chain-wheels 8 which support each drum 1, serves simultaneously as a driving wheel, and is for this purpose driven through 60 a toothed gearing 12 by an intermediate shaft 13 which in its turn is driven by means of a chain 14 from a main shaft 15 common to both drums and which is driven by means of a pulley 16 from a suitable motor, not illustrated in the drawing. The drums 1 are 65 guided by guide rollers 17 which are rotatably mounted at both sides of the water tank 5. The guide rollers on one side of the tank may suitably be adjustable in the vertical 70 direction, as indicated in Fig. 3.

The ribs 18 provided on the inside of the drums are formed by the sheet iron bars 2, which form the drums 1, being bent at one side—namely at the front side as taken in 75 the direction of rotation of the drum—inwards and then slightly backwards, in the manner illustrated in Fig. 4. In this manner the ribs obtain rounded edges 19 against which the logs strike during the rotation of 80 the drum, and since the ribs are also made somewhat resilient the shocks will be moderated, so that splitting and crushing of the ends of the logs is avoided as far as possible. The two drums 1 are so dimensioned that 85 their total length is at least 7.5 times as large as the drum diameter, which latter is chosen as small as it is possible to do for practical reasons. The speed of rotation of the drum is so chosen that the peripheral speed does 90 not exceed 1.2 meters per second. With these dimensions the height of fall of the logs within the drum, and thus also the violence of the impact of the logs against the ribs becomes as small as possible, so that the logs 95 will not be damaged.

Since the entire weight of the drums and of the logs within the drums rests on the chains 6, the friction between the drums and the chains, as well as the friction between the 100

chains and the driving chain-wheels 8 becomes so great that no teeth or the like are required for causing the drums to rotate.

The vertically adjustable mounting of the chain-wheels 8 also provides the advantage that it is easy, by means of the tackle blocks 11, to adjust the position of the drums in the vertical direction according as the chains 6 become worn.

10 During the rotation of the drum the logs gather mainly on that side of the drum where its periphery moves upwards, that is to say, on the left-hand side in Fig. 3. This results in the common centre of gravity of the drum 15 and logs being moved towards the same side, which in its turn causes the necessary supporting force to become greater at this side than at the opposite side of the drum. In order to avoid unnecessarily high stresses in 20 the chains 6, the left-hand parts of the same, which move upwards in Fig. 3, should be vertical or approximately vertical. At the same time the friction between the chains and the wheels 8 and between the chains and 25 the drum should be as great as possible, and in order to gain this end it is desirable that the tension in the two parts of each chain shall be as nearly equal as possible when the drum has its greatest speed and its greatest 30 load. For this purpose the chain-wheels 8 are given a less diameter than the drum, so that the descending parts of the chains 6—to the right in Fig. 3—will move in a direction inclined to the vertical line. By this arrangement a tension will be set up in these 35 parts of the chains which is greater than the vertical load on this side, and by choosing a suitable inclination of said descending chain parts it is possible to obtain a tension as nearly equal as possible in the two parts of each 40 chain.

During the operation of the barking drum there will as a rule be a more concentrated bark mixture within the drum than outside 45 the same in the water tank 5. In order to avoid this, there are secured to the outside of the drums 1 one or more bodies 20 which effect a stirring of the water during the rotation, whereby it becomes easier for the bark 50 to flow out through the slots 4. The rubbing or friction between the logs will also become more powerful, so that it is possible to decrease the quantity of water used, which is of particular importance in those cases when 55 hot water is used.

The construction illustrated in Fig. 5 differs from that above described mainly in that the chain-wheels 8' which are journalled on the levers 9' and which support the drum 60 1' by means of the chains 6', are not utilized as driving members. Instead, there are provided special chain driving wheels 21 which engage the ascending parts of the chains 6', said wheels 21 being connected to chain-wheels 22 which in their turn are driven by

means of chains 23 from chain-wheels 24 on the main shaft 15'.

The embodiments above described and illustrated in the drawings are only to be regarded as examples of the invention, as it will be understood that the same may be further modified in respect to their details in several ways without departing from the principle and scope of the invention. For instance, the shape of the ribs 18 may be changed as desired to suit various requirements, and said ribs may also be made as separate parts and be secured in suitable manner, for instance by means of rivets, to the inside of the drum. In certain cases it may be suitable to provide one or more rods or tubes within the drums diametrically through the same, for instance in the manner indicated by dotted and dashed lines in Fig. 3, said rods or tubes serving to effect a better stirring of the logs during the rotation of the barking drum.

I claim:

1. In a barking drum, the combination of a drum, two endless chains running around and supporting said drum, and a single chain wheel for each of said chains supporting the same, each such chain having its ascending part running in a substantially vertical direction and its descending part running in an inclined direction, each chain wheel being adjustable in the vertical direction.

2. In a barking drum, the combination of a drum, two endless chains running around and supporting said drum, a single chain wheel for each of said chains supporting the same, each such chain having its ascending part running in a substantially vertical direction and its descending part running in an inclined direction, each chain wheel being adjustable in the vertical direction, and means for driving one of said chain wheels.

3. In a barking drum, the combination of a drum, two endless chains running around and supporting said drum, a single chain wheel for each of said chains supporting the same, each such chain having its ascending part running in a substantially vertical direction and its descending part running in an inclined direction, a lever for each chain wheel on which such wheel is rotatably mounted, said lever being pivoted at one end, and means for vertical adjustment of the other end of said lever.

4. In a barking drum, the combination of a drum, two endless chains running around and supporting said drum, a single chain wheel for each of said chains supporting the same, each such chain having its ascending part running in a substantially vertical direction and its descending part running in an inclined direction, a lever for each chain wheel on which such wheel is rotatably mounted, said lever being pivoted at one end, means for vertical adjustment of the other

end of said lever, and means for driving one of said chain wheels.

5. In a barking drum, the combination of a drum, ribs on the inside of said drum, said ribs being resilient and having rounded edges, two endless chains running around and supporting said drum, and a single chain wheel for each of said chains supporting the same, each such chain having 10 its ascending part running in a substantially vertical direction and its descending part running in an inclined direction, each chain wheel being adjustable in the vertical direction.

15 6. In a barking drum, the combination of a drum, a water tank in which said drum is submerged, two endless chains running around and supporting said drum, a single chain wheel for each of said chains supporting the same, each such chain having its ascending part running in a substantially vertical direction and its descending part running in an inclined direction, each chain wheel being adjustable in the vertical direction, 20 and a stirring body secured to the outside of said drum.

JOHN STRINDLUND.
